UNITED STATES PATENT OFFICE.

SEVERO CAMPO FREGOSO, OF BRIGHTON, ENGLAND, ASSIGNOR OF ONE-HALF TO
JOHN RICHARD RYMAN, OF WIVERLY, SURREY, ENGLAND.

INTERNAL-COMBUSTION AND OTHER ENGINE.

1,285,106.

Specification of Letters Patent. Patented Nov. 19, 1918.

Application filed December 21, 1917. Serial No. 208,252.

To all whom it may concern:

Be it known that I, SEVERO CAMPO FREGOSO, a subject of the King of Italy, residing at 26 Lower Rock Gardens, Brighton, in the county of Sussex, England, have invented certain new and useful Improvements in and Relating to Internal-Combustion and other Engines, of which the following is a specification.

- 10 This invention relates to internal combustion engines and the like.
- 15 The primary object of my invention is to provide an engine working upon an improved principle of design, whereby an engine can be produced which is extremely compact, very light and powerful, well balanced as regards its moving parts, so that undesirable strains are eliminated, and which possesses many other important manufacturing and working advantages as compared with internal combustion engines as at present constructed.

20 The engine also embodies an improved mechanical construction for transforming the linear movement of the piston, or pistons, into the required rotary movement of the crank-shaft, or shafts, without the use of oscillating connecting rods, or cross heads, thus permitting a very simple and compact 25 construction to be obtained. This method of converting linear into rotary motion may also be adapted to other engines.

30 In the typical method of constructing an engine according to my invention, I provide a cylinder, which may be of any suitable metal or alloy of metals. Within this cylinder are fitted two pistons. The piston which is nearest to the crank is furnished preferably with one rod, which may be tubular, 35 and which is rigidly attached, in any ordinary way, to the piston. This rod passes through a diaphragm between the bottom of the cylinder and the crank chamber, a suitable gland being provided through which 40 the said rod passes. The other piston is provided with a rod connected at the outside to a transverse bar, which bar is connected by means of rods passing down outside and parallel to the sides of the cylinder and 45 through suitable glands into the crank chamber, to the two frames or devices operating upon the outer throws of a three throw crank or cranks, as hereinafter described, the 50 rod or rods of the first mentioned piston 55 being connected to a frame or equivalent de-

vice operating the center throw or throws of the crank or cranks.

55 I provide an annular chamber around the ends of the cylinder in the neighborhood of the diaphragm communicating by ports, preferably located in rows, with the interior of the cylinder, and I provide at the upper end of the cylinder a series of exhaust ports, suitably communicating with the exhaust 60 passages.

65 The cycle of operation of the engine will be readily understood. The explosive mixture is introduced, under pressure through a suitable non return valve into the space between the inner piston and the diaphragm, 70 when the piston is moving up the cylinder. On the return stroke the mixture is first compressed and then forced around from behind the inner piston to the space in the cylinder between the pistons. It is then compressed 75 between the two pistons, as they approach one another, fired at the proper time, and the pistons are driven apart communicating the motion through the rods to the crank 80 shaft or shafts. As the upper piston reaches the top of its stroke, the exhaust ports are uncovered, and the products of combustion escape, the rush of the incoming mixture assisting to scavenge the engine.

85 In some cases, in place of introducing explosive mixture into the annular chamber, I may introduce air which is compressed and forced around or transferred to the space between the pistons the fuel being injected at the proper time, upon the Diesel or semi- 90 Diesel principle.

95 For converting the linear motion into rotary motion I prefer to provide an arrangement of the following description:

100 Suitably mounted in the crank case are two three throw cranks at equal distances apart on each side of the center line of the cylinder or cylinders. The corresponding crank pins of the two cranks are connected by devices which I term bridges, so that 105 as the cranks rotate, the pins which pass through suitable bearings in the bridges cause the same to follow circular paths moving always parallel to themselves. Embracing each bridge is a device through 110 which the bridge can slide, and this device is attached to the extremity of the rod in connection with the inner piston or to one of the rods in connection with the outer piston as the case may be.

110

In this way, as the pistons are operated the linear motion of the rods causes the devices to be pushed backward and forward which in turn causes the bridges connecting the crank pins to be also pushed backward and forward and at the same time to slide transversely communicating a rotary motion to the shafts.

In some cases, in place of connecting the outer piston to a bar, which is in turn connected by means of rods to the devices in connection with the crank shaft or shafts, I may provide the outer piston with a central rod, which passes down through a suitable gland in the inner piston and is connected to the device working with the center throw of the crank or cranks, the inner piston in this case being provided with side rods passing through the diaphragm to the devices in connection with the outer throws of the three cranks.

In the case of hollow piston rods a continuous flow of air can be provided, entering the crank case and passing out through the hollow rods.

In order that my said invention may be more clearly understood I will now proceed to describe the same with reference to the drawing accompanying this specification, which shows by way of example a two cylinder engine constructed according to my invention.

Figure 1 is a sectional elevation of the engine and Fig. 2 is a similar view with a sectional portion at right angles to the plane of section in Fig. 1.

The same letters and numerals of reference are employed to denote the same parts in all the views.

40 *a, a* are two open ended cylinders, of any suitable metal or alloy of metals such as a good aluminium alloy. *b* is a crank case located between the cylinders *a*. This crank case may be open to the atmosphere.

45 Between the cylinders *a* and the crank case *b* are diaphragms *c*. In each of the cylinders *a* are fitted two pistons, an inner piston *d* and an outer piston *e*. Each of the inner pistons *d* is provided with a piston rod *f*, this rod being rigidly attached to the center of the piston in any suitable manner. The rod *f* passes through suitable contractile rings, glands or the like 3 fitted in the diaphragms *c*.

50 55 The outer piston *e* is provided with a bifurcated rod *g* which is attached at the inner end to the center of the piston *e*, the outer end of the arm of the fork *g* being attached to a bar *h*. *j, j* are two rods which are attached at their outer ends to the extremities of the bar *h*, and which pass down outside and parallel to the walls of the cylinder, through contractile rings glands or the like *k* into the crank case.

60 65 *m, m* are two crank shafts, which may be

hollow. They are provided with three throw cranks, the central throw in each crank being at 180° or thereabout from the outer throws. The center throw is denoted by *m*¹ and the outer throws by *m*².

70 Corresponding inner throws *m*¹ are connected by a bridge *n*¹ and the corresponding outer throws *m*² are connected by bridges *n*². The bridges are provided with plain, roller or ball bearings or equivalent devices 75 through which the crank pins pass.

Suitably attached to the inner end of each of the rods *f* is a slide or skate *p*¹, which operates the bridge *n*¹, one of the said slides or skates coming on each side of the bridge 80 and being connected to the opposite slide or skate by means of straps *q*¹, so that a frame or device is formed by the skates and straps which embraces the bridge and through which the bridge is enabled to slide. 85

Similar skates *p*² and straps *q*² are provided in connection with the bridges *n*².

r is an annular chamber extending around one end of each of the cylinders *a* in the neighborhood of the bottom thereof. *s* are 90 rows of ports opening into the cylinder. This annular chamber is in connection with the source of supply of explosive mixture or with the air supply where the engine is to be worked upon the Diesel or semi-Diesel 95 principle. A light non-return valve *v* is fitted between the annular chamber and the inlet pipe *x*. *t* is another annular chamber, communicating by means of ports *w* with the interior of the cylinder and with a suitable exhaust pipe. 100

The particular engine represented is provided with air cooling fins, but it is of course to be understood that the engine may be constructed so that it can be water cooled. 105

8 and 9 are two oil-pipes extending between the inner ends of the corresponding rods of the inner and outer pistons and which are adapted to slide within sleeves 110 to provide for establishing a continuous 110 oil-path from the oil-intake through the sleeves to the inside of the pipe 3.

The pipe 8 is further in communication with oil ways drilled through the center of the piston rod *f* and these again are in 115 communication with other oil ways drilled radially through the piston heads *d* and terminating at the walls of the piston between the two sets of packing rings.

The pipe 9 is similarly in communication 120 with oil ways drilled through the outer piston rods *j*, the bifurcated rods *g* and the piston heads *e*. Alternatively, the piping may extend from the sleeves 10 to the center or to the walls of the pistons *e* following the 125 course of the outer rods and thus avoiding drilling through them.

The lubricating oil, which is delivered to the sleeves 10 under pressure by means of pipes leading from an oil pump or in 130

any other suitable manner is forced from the sleeves to the pipes 8 and 9 and from these pipes to the pistons *d* and *e*, through the series of oil ways as before indicated. 5 The lubricant is thus delivered directly between the surfaces contacting very much in the same way as it is delivered between the bearing surfaces on the crank shaft under present pressure feed systems.

10 The crank shaft system, with all other moving parts within the crank case may be lubricated by spray originating from the crank shaft itself or in any other suitable manner, the usual dry sump arrangement being preferably adopted.

15 The operation of the engine will be readily understood.

Supposing the parts to be in the position shown at the left hand side of Fig. 2, where 20 the pistons *d* and *e* are about to approach one another; as the piston *d* moves outward, the explosive mixture is forced in behind the said piston and into the space between the same and the diaphragm *c*.

25 On the return stroke of the piston, the mixture is compressed within the said space, and within the annular chamber *r* which is provided, as stated with a valve *v* for preventing the compressed mixture being driven 30 back to the reservoir or pump.

When the piston approaches the bottom of the stroke, the upper row of ports *s* becomes uncovered and the mixture is forced around or transferred to the space between 35 the two pistons, both from the annular chamber and the space at the back of the piston. Being now within the space in the cylinder, between the pistons *d* and *e*, which are approaching one another, it becomes 40 compressed and at or about the time when the said pistons are most nearly together it is exploded in the ordinary way by a sparking plug or plugs located at *z*.

When the pistons again recede from one 45 another, the outer piston *e* uncovers the ports *w* and exhaust takes place in the ordinary way.

The exhaust is assisted by the inrush of the fresh mixture and the working of the 50 ports is preferably so timed that the transfer ports are uncovered slightly after the exhaust ports have been opened.

The method of transmitting the power developed by the engine has already been 55 indicated it being understood that the power may be taken either from one of the shafts *h*, the other shaft working as an idle shaft, or that the drive may be communicated from both shafts, any appropriate gear being in 60 that case provided such as toothed gearing or a chain for concentrating the power upon an auxiliary shaft or coupling the two shafts together.

It will be understood that although I have 65 described a form of engine provided with

two cylinders, a larger number of cylinders may be employed and that in some cases, I may connect a single cylinder engine to a transmission gear of this description. My construction possesses particular advantages 70 in that a single cylinder is as well balanced as a multiple-cylinder engine.

Further advantages of this particular method of converting reciprocating into rotary motion are that it greatly reduces 75 vibration and shortens the engine, while the rods owing to their rigid attachment at both ends considerably assist in steadyng and guiding the pistons.

Although I have shown a pair of crank 80 shafts connected together by means of bridges, I may in some cases provide single crank shafts. In this case, with a two cylinder engine of the type just described with reference to the drawing, I provide 85 three rectangular or other frames which are adapted to slide in different planes in suitable guides in the crank chamber. The central frame has attached to each end thereof the inner ends of the central piston 90 rods, and this frame is provided with a transverse slideway, in which slides a block through which passes the central crank pin, with the intervention of ball or roller bearings, or other anti-friction devices. 95 Similar anti-friction devices may be provided if desired between the block and the slideway.

In a similar manner, the two other frames, one of which is located on each side of the 100 beforementioned central frame, are provided with sliding blocks through which pass the outer pins of the three throw cranks and the frames have connected to them the corresponding rods of the other piston. 105

With this construction, as the crank shaft is rotated, each of the blocks moves from side to side of its corresponding slideway and the motion of the rods is communicated to the crank shaft when the pistons are 110 driven as previously explained.

The particular details of construction may be varied considerably to suit requirements according to the uses for which the engine is intended, without departing from the 115 principle of my invention.

For instance, in some cases instead of providing two crank shafts equally distant from the axis of the cylinders, I may offset the position of the two crank shafts, so 120 as to bring one of them directly or almost directly in line with the said axis of the cylinders. In this case the second crank shaft acts as a mere guide to the bridges or equivalent devices operating on the crank 125 pins.

Or again, three or more crank shafts may be fitted parallel to one another, each bridge in this case linking the three or more corresponding pins of the said shafts.

The cylinders may be assembled in any desired engine unit in diverse manners according to the purposes of which the engine is designed, for instance in any of the following manners:—

(a) In a single row, all on one side of the crank case the one or more shafts being accordingly lengthened, and the three throw arrangement repeated, each set of throws being at a suitable and easily defined angle to the others.

(b) In a double or treble row, all on one side of the two or more parallel shafts, each set of two or more cylinders operating upon the same set of bridges and therefore working and firing in consonance.

(c) In one or more pairs of directly opposed cylinders, the cylinders on each side of the crank case being arranged in any of the methods just described.

In any of these cases, the crank shaft arrangement is capable of assuming any of the various methods of construction already explained.

What I claim and desire to secure by Letters Patent of the United States of America is:—

1. In an internal combustion engine, the combination of a crank-case having cylinders at opposite points thereon and in continuation of the chamber thereof, said cylinders having inner and outer pistons arranged therein, said pistons being provided with piston-rods, the piston-rods of the inner pistons being attached centrally thereof, the piston-rods of the outer pistons being lat-

erally connected thereto and extending longitudinally and guided through said crank-case, pairs of frames formed of connected skates and straps, the piston-rods of said inner and outer pistons being connected to pairs of said frames, crank-shafts hung in said crank-case and having alternating loops or "throws" and "bridges" coupling said crank-shafts together and having slidable engagement with the "skates" of said frames.

2. In an internal combustion engine, the combination of a crank-case having cylinders at opposite points and in continuation of the chamber thereof, said cylinders having inner and outer pistons arranged therein, said pistons being provided with piston-rods the piston-rods of the inner pistons being attached centrally thereof the piston-rods of the outer pistons being laterally connected thereto and extending longitudinally and guided through said crank-case, a pair of frames formed of connected "skates" and straps, the piston-rods of said inner and outer pistons being connected to pairs of said frames, crank-shafts hung in said crank-case and having loops or "throws" and "bridges" coupling said crank-shafts together and having slidable engagement with the "skates" of said frames, said cylinders having ported annular chambers and exhaust chambers at the respective ends of each cylinder together with a valved inlet and an exhaust outlet at the opposite ends of each cylinder respectively.

In testimony whereof I affix my signature.

SEVERO CAMPO FREGOSO
